CONVERSION OF HYDROCARBON OILS

Charles H. Angell, Chicago, Ill., assignor to Universal Oil Products Company, Chicago, Ill., a corporation of Delaware

Application May 16, 1935, Serial No. 21,746
Renewed June 5, 1937

7 Claims. (Cl. 196—48)

This invention refers to an improved process for the conversion of relatively high-boiling hydrocarbon oils or oils containing a substantial proportion of high-boiling materials wherein the 5 charging stock for the process is subjected to vaporization by being commingled with hot vaporous conversion products of the process, the resulting non-vaporous high-boiling components of the charging stock subjected to relatively mild 10 conversion conditions together with intermediate conversion products of the process previously subjected to more severe conversion conditions and the resulting residual liquid products subjected to 15 coking.

15 In one embodiment, the invention comprises subjecting intermediate conversion products of the process (reflux condensate) to conversion conditions of cracking temperature and superatmospheric pressure in a heating coil, introducing 20 the heated products into an enlarged reaction chamber also maintained at a substantial superatmospheric pressure, separating vaporous and liquid conversion products in the reaction chamber, withdrawing the vaporous conversion 25 products from the reaction chamber and introducing the same into a reduced pressure vaporizing chamber to which hydrocarbon oil charging stock for the process is supplied, withdrawing non-vaporous liquids, including high-boiling 30 components of the charging stock, from the vaporizing chamber and introducing the same into said reaction chamber wherein they are subjected to relatively mild conversion together with the heated products from said heating coil, 35 separately withdrawing residual liquid conversion products from the reaction chamber, subjecting the same to additional heating under non-coking conditions and introducing the heated materials into a coking zone wherein they are reduced to 40 substantially dry coke, introducing vaporous products from the coking zone into said vaporizing chamber, subjecting vaporous products from the vaporizing chamber to fractionation for the 45 formation of reflux condensate, comprising said intermediate conversion products which are supplied to the first mentioned heating coil, subjecting fractionated vapors of the desired end-boiling point to condensation and recovering the resulting distillate.

50 By this method of operation the excess heat contained in the vaporous products from the cracking and coking operations is utilized to effect substantial vaporization or topping of the charging stock, the low-boiling vaporous fractions of which are subjected to fractionation

together with the vaporous products from the cracking and coking operations with which they are commingled, while high-boiling components of the charging stock remaining unvaporized by contact with the hot vaporous products of the 5 process are returned to the reaction chamber and thereby subjected to relatively mild conversion, without passing through a heating coil, by contact in this zone with the heated products from the heating coil to which the reflux condensate 10 produced by fractionation of the vaporous conversion products and low-boiling fractions of the charging stock is supplied.

It is within the scope of the invention to effect 15 substantial vaporization of the charging stock in the vaporizing chamber by contacting the same in this zone with either the vaporous conversion products from the reaction chamber or the vaporous products from the coking chamber, or both, and the invention contemplates regulation 20 of the extent of vaporization to which the charging stock is subjected by regulating the quantity 25 of such vaporous products from the reaction chamber and from the coking chamber commingled with the charging stock in the vaporizing chamber. Any remaining vaporous products from the reaction chamber and/or from the coking chamber in excess of those required for effecting the desired degree of vaporization of the 30 charging stock are subjected to fractionation together with the vaporous products from the vaporizing chamber.

The accompanying diagrammatic drawing 35 illustrates one specific form of apparatus in which the invention may be accomplished. Referring to the drawing, heating coil 1 is located within a furnace 2 of any suitable form and the oil supplied to this zone, in the manner to be later more fully described, is heated therein to the desired conversion temperature preferably at a substantial superatmospheric pressure. The heated oil 40 is discharged from heating coil 1 through line 3 and valve 4 into reaction chamber 5.

Chamber 5 is also preferably maintained at a substantial superatmospheric pressure which may 45 be substantially the same or somewhat lower than that employed at the outlet from the preceding heating coil. Although not indicated in the drawing, chamber 5 is also preferably insulated in order to prevent the excessive loss of heat 50 therefrom by radiation so that conversion of the heated products supplied to this zone is continued therein. In the case here illustrated, separation of vaporous and liquid conversion products is accomplished in chamber 5, the liquid products 55

being withdrawn from the lower portion of the chamber to further treatment, as will be later more fully described, while the vaporous products are removed from any desired higher point in the chamber, such as, for example, through line 5 6, and may be directed, all or in part, through valve 7 in this line into vaporizing chamber 8, or regulated portion or all of these vapors may pass from line 6 through line 9, valve 10 and line 10 11 direct to fractionator 30.

Residual liquid conversion products are withdrawn from the lower portion of chamber 5 through line 13 and valve 14 to pump 15 by means of which they are supplied through line 15 16 and valve 17 to heating coil 18.

Heating coil 18 is located within a furnace 19 of suitable form capable of quickly heating the residual liquid passing through the heating coil to a relatively high temperature sufficient to 20 effect its subsequent reduction to coke in coking chamber 22, to which the highly heated residual liquid is supplied through line 20 and valve 21. The velocity of the residual liquid passing through heating coil 18 and the rates of heat transfer in 25 this zone are so regulated that the oil is quickly brought to the desired coking temperature without allowing it to remain in the heating coil and communicating lines for a sufficient length of time to permit any substantial formation and 30 deposition of coke therein.

Coking chamber 22 is preferably maintained at substantially atmospheric or a relatively low superatmospheric pressure although pressures up to 150 pounds, per square inch, or thereabouts, or 35 up to substantially the same pressure as that maintained at the outlet from heating coil 18 may be utilized in the coking chamber. It will be understood, of course, that although only a single coking chamber is shown in the drawing 40 any desired number of a plurality of such zones may be employed, when desired, and may be either simultaneously operated or, preferably, are alternately operated, cleaned and prepared for further operation so that the coking stage, in 45 common with the rest of the system, may be operated continuously. The heated residual liquid supplied to the coking chamber is reduced to substantially dry coke in this zone and the coke may be allowed to accumulate therein to be re- 50 moved from the chamber, in any well known manner not illustrated, after its operation is completed and after it has been isolated from the rest of the system. Chamber 22 is provided with a suitable drain-line 23 controlled by valve 55 24 which may also serve as a means of introducing steam, water or any other suitable cooling material into the chamber, after its operation is completed and after it has been isolated from the rest of the system, in order to hasten cooling 60 and facilitate the removal of coke from the chamber. Vaporous products are withdrawn from the upper portion of chamber 22 through line 25 and may be directed, all or in part, through line 26 and valve 27 into vaporizing 65 chamber 8, or all or a regulated portion of the vaporous products from the reaction chamber may pass through valve 28 in line 25 into line 11 and thence to fractionator 30.

Simultaneous with the operation above described, hydrocarbon oil charging stock for the process, preferably comprising an oil of relatively wide boiling range, such as crude petroleum, topped crude or the like, or an oil which contains a substantial proportion at least of high-boiling 70 materials, is supplied through line 31 and valve 75

32 to pump 33 by means of which it is fed through line 34 and valve 35 into vaporizing chamber 8.

Vaporizing chamber 8 is preferably operated at a substantially reduced pressure relative to that employed in chamber 5 and the charging 5 stock supplied to this zone is directly commingled therein with regulated quantities of the hot vaporous products from reaction chamber 5 and/or coking chamber 22 and is thereby subjected to appreciable vaporization. Suitable contacting 10 means such as bubble trays, packing, perforated pans, baffles or the like (not illustrated) or any desired combination of such means may be employed in chamber 8, when desired, for effecting intimate contact between the hot vaporous products and the charging stock. Contacting of the charging stock with the vaporous conversion products from the reaction chamber and coking chamber in chamber 8, aside from effecting substantial vaporization of the charging stock, 20 serves the additional purpose of partially cooling the vapors and thereby removing therefrom any undesirable high-boiling components such as entrained or dissolved tars and similar heavy liquids unsuitable as charging stock for heating coil 25 1. These undesirable high-boiling components of the vapors commingle in chamber 8 with the high-boiling components of the charging stock which remain unvaporized in this zone and the 30 commingled materials are removed from the lower portion of the vaporizing chamber through line 36 and valve 37 to pump 38 by means of which they are supplied through line 39 and valve 40 to reaction chamber 5.

In the particular case here illustrated, the relatively heavy oil from vaporizing chamber 8 enters the upper portion of reaction chamber 5 and is sprayed against the inner surface of the walls of the chamber by means of a suitable spray or spreader device indicated at 56. In this manner 35 the relatively heavy oil flows downward over the walls of the reaction chamber to the lower portion of this zone and is subjected during its passage through this zone to conversion under the conditions maintained in the reaction chamber. 40 The residual liquid products resulting from conversion of the high-boiling oils from chamber 8 collect in the lower portion of chamber 5 together with the residual liquids resulting from conversion of the heated products from heating coil 1 45 and pass therewith to coking, in the manner previously described. The manner of introducing the heavy oils from chamber 8 into chamber 5 and causing the same to flow downward over the inner surface of the walls of the chamber, aside 50 from accomplishing relatively mild conversion thereof, serves to wash the inner surface of the walls of the reaction chamber and thereby substantially prevent the accumulation of heavy tars 55 and pitch-like material on the walls of the chamber, thereby substantially preventing the formation and accumulation of coke in this zone. 60

Vaporous products, including the relatively low-boiling vaporized components of the charging stock as well as the components of the 65 vaporous conversion products supplied to chamber 8 which remain uncondensed in this zone, are withdrawn therefrom through line 11 and valve 12 and supplied, together with any portion of the vaporous products from reaction chamber 70 5 and/or coking chamber 22 not supplied to chamber 8, to fractionation in fractionator 30. The components of the vaporous products supplied to fractionator 30 boiling above the range 75 of the desired final light distillate product of the

process are condensed in this zone as reflux condensate, which is withdrawn, in the case here illustrated, from the lower portion of the fractionator through line 41 and valve 42 to pump 5 43, by means of which it is returned through line 44 and valve 45 to conversion, in the manner previously described, in heating coil 1.

It is, of course, also within the scope of the invention to separate the reflux condensate formed 10 in fractionator 30 into two or more selected relatively low-boiling and high-boiling fractions, any of which may, when desired, be removed from the system while one or more of said fractions may be subjected to conversion in heating coil 1 and, 15 when desired, other selected fractions may be subjected to independently controlled conversion conditions in one or more separate heating coils, not illustrated, heated products from which may be supplied, all or in part, to reaction chamber 5 20 or to vaporizing chamber 8 or to coking chamber 22.

Fractionated vapors of the desired end-boiling point are withdrawn, together with uncondensable gas produced by the operation, from the upper portion of fractionator 30 through line 46 and valve 47 and are subjected to condensation and cooling in condenser 48. The resulting distillate and gas pass through line 49 and valve 50 to collection and separation in receiver 51. Uncondensable gas may be released from the receiver through line 52 and valve 53. Distillate may be withdrawn from receiver 51 through line 54 and valve 55 to storage or elsewhere, as desired. When desired, a regulated portion of the distillate 30 collected in receiver 51 may be recirculated, by well known means not illustrated in the drawing, to the upper portion of fractionator 30, to serve as a refluxing and cooling medium for assisting fractionation of the vapors in this zone 35 and to maintain the desired vapor outlet temperature therefrom.

The invention is not limited to the specific method illustrated and described for reducing the residual liquid products from the reaction chamber to coke since any other well known method, including the use of a suitable heat carrying medium for assisting the coking operation as well as, when desired, an externally heated coking chamber or a coking retort of any well known 40 form, is readily adaptable to the process of the invention. The invention also contemplates the omission of the coking step of the process, when desired, in which case the process may be operated for the production of liquid residue from the 45 reaction chamber.

The preferred range of operating conditions which may be employed for accomplishing the objects of the present invention in an apparatus such as illustrated and above described will be 50 approximately as follows: The heating coil to which the reflux condensate is supplied may employ an outlet conversion temperature ranging, for example, from 850 to 950° F., or more, preferably with a superatmospheric pressure at this 55 point in the system of from 100 to 500 pounds, or more, per square inch. Any desired superatmospheric pressure within substantially the same range but no greater than that employed at the outlet from the heating coil may be utilized in 60 the succeeding reaction chamber. The vaporizing chamber is preferably operated at a substantially reduced pressure relative to that employed in the reaction chamber which may range, for example, from 100 pounds, or thereabouts, per 65 square inch down to substantially atmospheric 70 pressure.

The temperature to which the residual liquid from the reaction chamber is subjected in the heating coil to which it is supplied may range, for example from 900 to 1050° F., preferably with a relatively low superatmospheric pressure in this zone of the order of 20 to 150 pounds, or thereabouts, per square inch, although lower or higher pressures may be employed in this zone, when desired. Any desired pressure ranging from substantially atmospheric to 150 pounds, or thereabouts, per square inch, which, however, is no greater than the pressure employed in the preceding heating coil, may be utilized in the coking zone. The pressures employed in the fractionating, condensing and collecting portions of the system may be substantially equalized or somewhat reduced relative to the pressure employed in the preceding portions of the system communicating therewith.

As a specific example of an operation of the 20 invention as it may be accomplished in an apparatus such as illustrated and above described, the charging stock, which comprises a California crude of about 20.5° A. P. I. gravity containing approximately 12 per cent of gasoline fractions 25 boiling up to 400° F. and about 40 per cent of materials boiling up to 572° F., is supplied to the vaporizing chamber which is operated at a superatmospheric pressure of approximately 50 pounds per square inch, the charging stock being therein 30 subjected to appreciable vaporization by contact with the total vaporous products from the coking zone as well as a portion of the vaporous products from the reaction chamber. The remaining portion of the vaporous products from the reaction chamber are subjected, together with the vaporous products from the vaporizing chamber, to fractionation for the formation of reflux condensate. The reflux condensate is subjected in the heating coil to an outlet conversion temperature of approximately 950° F. at a superatmospheric pressure of about 350 pounds per square 35 inch and the highly heated products are supplied to a reaction chamber maintained at substantially the same pressure. Non-vaporous liquid 40 products from the vaporizing chamber are also supplied to the reaction chamber and sprayed against the inner surface of the walls in the upper portion of this zone. Residual liquid is withdrawn from the reaction chamber, quickly heated 45 in a separate heating coil to a temperature of approximately 1000° F. at a superatmospheric pressure of about 50 lbs. per square inch and introduced into a coking chamber operated at substantially the same pressure wherein it is reduced 50 to substantially dry coke. This operation will produce, per barrel of charging stock, approximately 60 per cent of 400° F. end-point motor fuel of good antiknock value and approximately 100 pounds of low volatile coke of uniform quality 55 and good structural strength, the remainder being chargeable, principally, to uncondensable gas.

I claim as my invention:

1. In a process for the conversion of hydrocarbon oils wherein intermediate liquid conversion 65 products, comprising reflux condensate formed by fractionation of the vaporous conversion products of the process, are subjected to conversion conditions of cracking temperature and superatmospheric pressure in a heating coil and communicating reaction chamber, vaporous and liquid conversion products separated in the reaction chamber, separately withdrawn therefrom and the latter subjected to coking in a separate coking zone, the improvement which comprises with- 70 75

drawing vaporous products from the coking zone and introducing a portion thereof into a vaporizing chamber, supplying hydrocarbon oil charging stock for the process to the vaporizing chamber wherein it is subjected to appreciable vaporization by contact with said portion of the hot vaporous products from the coking zone, withdrawing nonvaporous liquid products from the vaporizing chamber and returning the same to the reaction chamber wherein they are subjected to relatively mild conversion by contact with the heated products from said heating coil, supplying vaporous products from the vaporizing chamber, together with vaporous products from the reaction chamber and the remaining portion of the vaporous products from the coking zone, to fractionation for the formation of said reflux condensate which is returned to the heating coil for further conversion, subjecting fractionated vapors of the desired end-boiling point to condensation and recovering the resulting distillate.

2. In a process for the conversion of hydrocarbon oils wherein intermediate liquid conversion products, comprising reflux condensate formed by fractionation of the vaporous conversion products of the process, are subjected to conversion conditions of cracking temperature and superatmospheric pressure in a heating coil and communicating reaction chamber, vaporous and liquid conversion products separated in the reaction chamber, separately withdrawn therefrom and the latter subjected to coking in a separate coking zone, the improvement which comprises supplying a portion of the vaporous products withdrawn from the coking zone and a portion of the vaporous products withdrawn from the reaction chamber to a vaporizing chamber, supplying hydrocarbon oil charging stock for the process to said vaporizing chamber wherein it is subjected to appreciable vaporization by contact with said portions of the hot vaporous products from the coking zone and reaction chamber, withdrawing non-vaporous liquids from the vaporizing chamber and introducing the same into said reaction chamber wherein they are subjected to relatively mild conversion by contact with the heated products from said heating coil, combining vaporous products from the vaporizing chamber with the remaining portions of the vaporous products from the reaction chamber and coking zone and subjecting the resultant mixture to fractionation for the formation of said reflux condensate which is returned to the heating coil for further conversion, subjecting fractionated vapors of the desired end-boiling point to condensation and recovering the resulting distillate.

3. In a process for the conversion of hydrocarbon oils wherein intermediate liquid conversion products, comprising reflux condensate formed by fractionation of the vaporous conversion products of the process, are subjected to conversion conditions of cracking temperature and superatmospheric pressure in a heating coil and communicating reaction chamber, vaporous and liquid conversion products separated in the reaction chamber and separately withdrawn therefrom, the improvement which comprises introducing a portion of the vaporous products withdrawn from the reaction chamber into a vaporizing chamber, introducing hydrocarbon oil charging stock for the process into the vaporizing chamber wherein it is subjected to appreciable vaporization by contact with said portion of the hot vaporous products from the reaction chamber, withdrawing non-vaporous liquids from the va-

porizing chamber and introducing the same into the reaction chamber wherein they are subjected to relatively mild conversion by contact with the heated products from said heating coil, withdrawing vaporous products from the vaporizing chamber, combining the same with the remaining portion of the vaporous products from the reaction chamber and subjecting the resultant mixture to fractionation for the formation of said reflux condensate which is returned to the heating coil for further conversion, subjecting fractionated vapors of the desired end-boiling point to condensation and recovering the resulting distillate.

4. A process for the conversion of hydrocarbon oils which comprises subjecting intermediate liquid conversion products, comprising reflux condensate formed by fractionation of the vaporous conversion products of the process, to conversion conditions of cracking temperature and superatmospheric pressure in a heating coil and communicating reaction chamber, separating vaporous and liquid conversion products in the reaction chamber, separately withdrawing the same therefrom, heating the residual liquid conversion products withdrawn from the reaction chamber to a high temperature under non-coking conditions, introducing the heated materials into a coking chamber, reducing the same therein to substantially dry coke, introducing regulated portions of the vaporous products withdrawn from the coking chamber and from the reaction chamber into a vaporizing chamber, introducing hydrocarbon oil charging stock for the process into the vaporizing chamber whereby it is subjected to appreciable vaporization by contact with said portions of the hot vaporous products supplied to this zone, withdrawing non-vaporous liquid from the vaporizing chamber and introducing the same into the reaction chamber wherein they are subjected to relatively mild conversion by contact with the heated products from said heating coil, withdrawing vaporous products from the vaporizing chamber and subjecting the same, together with the remaining vaporous products from the reaction chamber and the coking chamber, to fractionation for the formation of said reflux condensate which is returned to the heating coil for further conversion, subjecting fractionated vapors of the desired end-boiling point to condensation and recovering the resulting distillate.

5. A conversion process which comprises fractionating hydrocarbon vapors formed as herein-after set forth, heating resultant reflux condensate to cracking temperature under pressure in a heating coil and separating the same into vapors and unvaporized oil in a reaction chamber, removing the unvaporized oil and further distilling the same in a second chamber, contacting a portion of the vapors from the second chamber with charging oil for the process to vaporize a portion of the charging oil, introducing the unvaporized portion of the charging oil to the reaction chamber, supplying vapors from the reaction chamber, the vapors from said contacting step and the remaining portion of the vapors from the second chamber to said fractionating step, and finally condensing the fractionated vapors.

6. A conversion process which comprises fractionating hydrocarbon vapors formed as herein-after set forth, heating resultant reflux condensate to cracking temperature under pressure in a heating coil and separating the same into vapors and unvaporized oil in a reaction chamber, removing the unvaporized oil and further distilling

the same in a second chamber, contacting a portion of the vapors from the reaction chamber with charging oil for the process to vaporize a portion of the charging oil, introducing the unvaporized portion of the charging oil to the reaction chamber, supplying vapors from the second chamber, the vapors from said contacting step and the remaining portion of vapors from the reaction chamber to said fractionating step, and finally condensing the fractionated vapors.

7. A conversion process which comprises fractionating hydrocarbon vapors formed as herein-after set forth, heating resultant reflux condensate to cracking temperature under pressure in a heating coil and separating the same into vapors

and unvaporized oil in a reaction chamber, removing the unvaporized oil and further distilling the same in a second chamber, contacting a portion of the vapors from the second chamber and a portion of the vapors from the reaction chamber with charging oil for the process to vaporize a portion of the latter, introducing the unvaporized portion of the charging oil to the reaction chamber, supplying the vapors from said contacting step and the remaining portions of the vapors from said chambers to the fractionating step, and finally condensing the fractionated vapors.

CHARLES H. ANGELL.
